DESIGN FOR A COMBINATION SUPPORTING FRAME AND FLOWER HOLDER

Lewis P. Weil, Germantown, Pa.

Application November 4, 1939, Serial No. 88,033

Term of patent 7 years

To all whom it may concern:

Be it known that I, Lewis P. Weil, a citizen of the United States, residing in Germantown, in the county of Philadelphia, State of Pennsylvania, have invented a new, original, and ornamental Design for a Combination Supporting Frame and Flower Holder, of which the following is a specification, reference being had to the accompanying drawing, forming part thereof.

Fig. 1 is a front elevational view of a com-

bination supporting frame and flower holder showing my design.

Fig. 2 is a sectional view taken on line 2—2 of Fig. 1, and

Fig. 3 is a sectional view taken on line 3—3 of Fig. 1.

I claim:

The ornamental design for a combination supporting frame and flower holder, as shown.

LEWIS P. WEIL.
